US0D1083287S

(12) **United States Design Patent** (10) **Patent No.:** **US D1,083,287 S**
(45) **Date of Patent:** **** Jul. 8, 2025**

(54) **DEFENSIVE STORAGE BOX**

(71) Applicant: **Kongming Wei**, Suzhou (CN)

(72) Inventor: **Kongming Wei**, Suzhou (CN)

(**) Term: **15 Years**

(21) Appl. No.: **29/929,701**

(22) Filed: **Feb. 23, 2024**

(30) **Foreign Application Priority Data**

Jan. 18, 2024 (CN) 202430035183.5

(51) **LOC (15) Cl.** **99-00**

(57) **CLAIM**

The ornamental design for a defensive storage box, as shown and described.

DESCRIPTION

FIG. 1 is a front perspective view of a defensive storage box showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an enlarged portion view taken from encircled portion, "8," in FIG. 1.

The dash-dash broken lines in the drawings depict the portions of the defensive storage box that form no part of the claimed design.

The dot-dash broken lines in the drawings depict the boundaries of the enlarged portion view of FIG. 8 in FIGS. 1 and 8 and form no part of the claimed design.

1 Claim, 8 Drawing Sheets
